CLAIM

The ornamental design for a "combined display and button for portable communication receiver", as shown and described.

DESCRIPTION

FIG. 1 is a front elevational view of a "combined display and button for portable communication receiver" showing my new design;

FIG. 2 is a bottom plan view of FIG. 1;

FIG. 3 is a top plan view of FIG. 1;

FIG. 4 is a left side elevational view of FIG. 1;

FIG. 5 is a right side elevational view of FIG. 1; and

FIG. 6 is a front, left side and bottom perspective view of FIG. 1;

The broken lines showing a portable communication environment in FIGS. 1-6 are for illustrative purposes only and form no part of the claimed design.

FIG. 7 is a front elevational view of a "combined display and button for portable communication receiver" showing an alternate embodiment of my new design;

FIG. 8 is a bottom plan view of FIG. 7;

FIG. 9 is a top plan view of FIG. 7;

FIG. 10 is a left side elevational view of FIG. 7;

FIG. 11 is a right side elevational view of FIG. 7; and,

FIG. 12 is a front, left side and bottom perspective view of FIG. 8.

The broken lines showing a portable communication environment in FIGS. 7-12 are for illustrative purposes only and form no part of the claimed design.
